UNITED STATES PATENT OFFICE.

SIMON ZINN, OF NEW YORK, N. Y.

DESIGN FOR A FRAME FOR POCKET-BOOKS.

SPECIFICATION forming part of Design No. 24,146, dated March 26, 1895.

Application filed December 18, 1894. Serial No. 532,259. Term of patent 7 years.

To all whom it may concern:

Be it known that I, SIMON ZINN, a citizen of the United States, residing at New York, in the county and State of New York, have invented and produced a new and original Design for Frames for Pocket-Books and other Articles, of which the following is a specification, reference being had to the accompanying drawings, showing a part thereof.

10 This design has for its object to provide a novel, ornamental and characteristic frame for pocket-books, purses, bags, and similar articles.

15 The design consists in a frame having an oblong portion, joined at its ends to shorter oblong portions with indentations between the long and short oblong portions, and longitudinal, cylindrical portions having laterally enlarged and indented portions joining 20 them to the short oblong portions.

The design is illustrated by the accompanying drawings, in which—

25 Figure 1 is a plan view of a pocket-book frame embodying my design; and Fig. 2 is a side elevation of the same.

In the drawings the numeral 1 indicates an

oblong portion, joined at its ends to shorter oblong portions 2, and 3 are indentations between the short and long oblong portions 2. The long cylindrical portions 4 are joined to the 30 short oblong portions 2 by laterally enlarged portions 6 and indented portions 5. The numeral 7 indicates a lateral lip projecting from the long oblong portion 1.

The design provides a handsome pocket- 35 book, or similar frame which presents a distinguishing and characteristic appearance.

What I claim is—

The design for the frame of a pocket-book, having the oblong portion 1, shorter oblong 40 portions 2, indentations 3, long cylindrical portions 4, lateral enlargements 6, and indentations 5, substantially as shown and described.

In testimony whereof I have hereunto set 45 my hand in the presence of two subscribing witnesses.

SIMON ZINN.
